Primary Examiner — Jonathan J Han(74) *Attorney, Agent, or Firm* — Kristin D. Wheeler(57) **CLAIM**

The ornamental design for a shoe, as shown and described.

DESCRIPTION

FIG. 1 is a top perspective view of a shoe showing my new design;

FIG. 2 is a top plan view of the shoe of a shoe, thereof; FIG. 3 is a lateral side elevation view of the shoe, thereof; FIG. 4 is a medial side elevation view of the shoe, thereof; FIG. 5 is a rear elevation view of the shoe, thereof; FIG. 6 is a front elevation view of the shoe, thereof; and, FIG. 7 is a bottom plan view of the shoe thereof.

In FIGS. 1–7, the broken lines on the upper of the shoe, including any laces, eyelets, tongue or logos, form no part of the claimed design. Also, the broken lines showing a shoe outsole, including any logos, form no part of the claimed design.

1 Claim, 6 Drawing Sheets(56)
